Specification of Letters Patent. Patented Mar. 26, 1918.

Application filed September 28, 1915. Serial No. 53,083.

To all whom it may concern:

Be it known that we, GEORGE W. HARRIS, and VINCENT O. RITCHAY, citizens of the United States, residing at Coraopolis, in the county of Allegheny and State of Pennsylvania, have invented certain new and useful Improvements in Furnaces, of which the following is a specification.

The present invention relates to improvements in furnaces and especially to furnaces adapted to be used for heating, re-heating and annealing purposes as may be desired.

The furnace herein disclosed is designed more particularly for the treatment of automobile spring leaves, a character of work requiring careful treatment and involving several steps differing from each other to such an extent that prior practice practically required the use of different furnaces to produce the result.

For instance, the bars are initially heated to a temperature approximating 2000° F., whereupon, they are removed and shaped; each bar is then re-heated at a temperature approximating 1600° F., then subjected to a tempering bath, after which it is placed in an annealing or drawing furnace for final treatment, the latter being at a heat approximating 900° F.

Obviously, these relative wide variations in heat conditions for the several steps render it a difficult matter to produce the several operations in a single furnace such as that commonly employed for this purpose, owing to the length of time required to bring the furnace to the desired temperature and the greater difficulty in maintaining such temperature approximately uniform. The latter difficulty is increased by the fact that in operation, the bars are generally introduced and removed from the furnace individually and hence require the opening of the heating chamber each time when such change is made, the opening of the chamber permitting inrush of cold air which tends to vary the temperature, especially at the entrance end of the chamber.

These difficulties, together with the necessity for completing the series of operations as quickly as possible, have practically required the use of independent furnaces for different steps, it having been found more economical to employ individual furnaces

than to attempt to vary the temperatures of a single furnace in carrying out the several steps.

The present invention is designed with a view to permitting these successive operations to be provided in a single furnace and with greater economy. In actual practice involving an operation covering a series of months, a furnace of the type disclosed herein has met all of the conditions required for this particular use. This result is brought about by the fact that the time required for bringing the furnace to its working temperature in the initial step is reduced more than fifty per cent., and when this temperature is reached, it is maintained throughout the period required in completing the first stage operation of the bars which are being treated in the first stage. This ability to rapidly change the temperature of the operating or treating chamber of the furnace then enables the furnace to be quickly brought to the temperature for the second stage, and, similarly, the temperature can be again quickly changed for the purposes of the third stage. In addition, the temperature of the treating chamber is maintained substantially uniform, the heating arrangements being such that opening of the chamber is ineffective to materially vary this temperature.

Practical tests of the furnace referred to have demonstrated that the particular construction and arrangement of the furnace will permit operation at temperatures ranging from 400 to 3000° F., the temperature being maintained substantially uniform at any desired point within this range. Furthermore, it has been found that these results are obtainable through the expenditure of a greatly reduced amount of fuel, the furnace referred to operating with the use of approximately one-third to one-half the amount of gas required in other furnaces heretofore employed for the purpose, the cost of fuel per ton of material treated being decreased to approximately one-third in the present apparatus.

To these and other ends, the nature of which will be readily understood as the invention is hereinafter disclosed, our invention consists in the improved construction and combination of parts hereinafter fully

described, illustrated in the accompanying drawings, and more particularly pointed out in the appended claims.

In the accompanying drawings, in which 5 similar reference characters indicate similar parts in each of the views,

Figure 1 is a front elevation of a double or twin furnace constructed in accordance with the present invention.

10 Fig. 2 is a fragmentary view of the rear of the furnace.

Fig. 3 is a vertical sectional view taken on the line 3—3 of Fig. 1.

15 Fig. 4 is a vertical sectional view taken on the line 4—4 of Fig. 3.

Fig. 5 is a horizontal sectional view taken on the line 5—5 of Fig. 3.

Fig. 6 is a vertical sectional view taken on the line 6—6 of Fig. 3.

20 Fig. 7 is a detail view, partly in elevation and partly in section of a preferred form of burner.

The furnace is preferably of the twin type, thus practically producing two individual furnaces for operation purposes, the 25 particular arrangement of parts disclosed herein being such that it is possible to operate the individual furnaces concurrently at different temperatures. Obviously, the same 30 general ideas may be employed in a single furnace, the arrangement of flues being varied in correspondence but retaining the same general characteristics.

10 designates the bottom setting of the 35 furnace, said setting supporting the working parts of the furnace. 11 designates the operating or treating chamber which extends from the front toward the rear a suitable distance, said chamber having at its 40 rear a bridge wall 12 which projects above the plane of the bottom of the chamber a suitable distance, said bridge wall forming a continuation of a wall 13 of the combustion chamber indicated at 14, the latter 45 being at the rear of the furnace and having its length equal to the width of chamber 11.

As shown more particularly in Figs. 3, 4 and 6, the upper wall of the combustion chamber 14 is formed stepped as indicated 50 at 15, this arrangement not only serving to change the direction of flow of the products of combustion, but also tending to so affect the gases, etc., from the combustion chamber as to better equalize the delivery of the 55 gases, etc., into the chamber 11.

The fuel employed is preferably gas or oil, although other forms of fuel may be employed. This is introduced into the combustion chamber through a suitable burner, 60 a preferred form of which is shown in Fig. 7, the burner being indicated generally at 16 and having a pair of nozzles 17, these nozzles entering suitable ports 18 in the rear wall of the furnace. As shown more particularly in Fig. 2, air is admitted into the 65

combustion chamber below the nozzle 17 through ports 19, the admixture of air and gas within the combustion chamber being readily obtained, and through the particular form of walls of the combustion chamber, 70 provision is made for effective combustion, the products being directed into chamber 11 over bridge wall 12, the stepped wall 15 aiding in properly directing these products. 75

At the front end of chamber 11, the bottom wall of said chamber is formed with a plurality of openings 20, these openings being adjacent to the inlet to chamber 11, each opening leading downwardly into a flue 21, the latter extending rearwardly to a point 80 adjacent wall 13 where it connects with a flue 22 leading to the stack, the connection being by lateral passageway 23.

The general arrangement of the flues is best shown in Fig. 5. In this view, each 85 flue 22 is shown as forming the outlet for a pair of flues 21, this arrangement, in the twin design disclosed herein, providing for the employment of three flues 22 and six 90 flues 21, the nine flues being arranged in sets of three, the flues 22 being located respectively at the center of the furnace and at the opposite sides. As shown more particularly in Fig. 6, this arrangement provides three rearwardly extending flues for 95 each of the two treating chambers, the flues 22 being located in the walls of the furnace between the two chambers and on the outer sides of such chambers.

As a result, we not only provide for heating 100 the bottom wall or floor of chamber 11 from beneath, but also practically insure that the products employed for this purpose are of substantially uniform temperature, this being due to the fact that each of the 105 three flues which provide this heating action are of similar length and have the gases traversing them in the same direction. As shown more particularly in Fig. 4, the front 110 ends of flues 22 lead into flues 24 which extend to the stack 25.

The flues 21 extend to the front wall of the furnace, and may be permanently closed in advance of opening 20, but we prefer to close these advance ends through the use of 115 loose bricks 21^a which are not only readily removed for cleaning purposes, but which, in addition, may provide a small leakage of air into the flues.

Each treating chamber is closed by a door 120 26, these doors being preferably arranged to be slidable vertically and operable by the foot of the furnace operator, this result being obtained by the use of a pivoted lever 27 carrying a member 28 which is connected to the door 26 by a suitable connection, indicated as a wire rope 29. The opposite end of lever 27 is connected to a treadle 30 by suitable connection 31, the arrangement being such that when the operator places his 125 130

foot on treadle 30, lever 27 will be rocked to raise door 26, said door returning to its closing position by its weight when treadle 30 is released by the operator. A suitable counterpoise 32 may be employed on the lever 27 to permit easier manipulation of the door 26 by the operator who, at this time, is also expected to be engaged in manipulating the contents of the treating chamber 11.

10 From the drawings and the above description, it will be seen that the furnace gases are initially led into the treating chamber 11, being directed thereto over bridge wall 12 and toward the top of said chamber, these 15 gases then traversing the chamber to the front end of the latter where they pass downwardly through openings 20 into flues 21, the latter leading the gases rearwardly under the chamber bottom to the rear end 20 of the chamber, where the gases are then passed to flues 22 *en route* to the stack 25. While the gases are thus brought directly into the treating chamber 11, the bridge wall 12 acts to prevent the flame, etc., from sweeping 25 the floor of this chamber, thereby providing a space or zone immediately above the floor which, while directly open to the remainder of the chamber, is substantially free from the direct passage of the gases 30 therethrough, the gases traversing the top of chamber 11 and thus providing a heat radiation effect on the bottom of the chamber throughout the length of travel of the gases within the chamber 11. Consequently, this 35 zone is substantially immune from liability of direct contact of flame and the contents of the zone, so that articles which may be placed within this zone below the top plane of the bridge wall 12 are practically immune from damage by flame contact. As heretofore pointed out, a furnace constructed in accordance with the present invention has been in constant service for a 40 number of months, and during this period, practically no loss has been had through damage in this form although the particular character of the work operated upon is such as to necessitate close inspection for such damage.

45 As will be seen in Fig. 3, the wall 13 is inclined forwardly toward its top. This places in the path of the incoming gases and air a surface which tends to force the mixture into a curved path of movement within the combustion chamber, thus tending to carry the mixture into contact with the portion 15 in a manner to provide a more thorough combustion of the mixture. This action is such that, for certain purposes, it may 50 be possible to omit the bridge wall 12 and still form the zone heretofore referred to, since the direction of flow of the gases forced by this inclined wall would tend to carry them to the top of the treating chamber and 55 thus maintain the zone substantially free from flame contact. However, we prefer for general operation and especially for the particular use heretofore pointed out, to employ the bridge wall structure referred to, the inclination of wall 13 having a similar effect 60 where the bridge wall is employed.

65 As will be readily understood, the ability to employ the heat direct from the gases themselves, in addition to the heat radiation which may be provided by the top walls of the chambers not only provides for rapid heating of the chamber, but also places this heat in such manner that it tends to prevent the entrance of cold air into the chamber when the door 26 is opened to change the 70 contents, a comparatively short period due to the facilities for making the changes. This result is due to the fact that the heated gases must traverse the chamber to its front in seeking the outlets for the gases. Should there be any tendency of the colder air to enter when the door is opened, the fact that openings 20 are adjacent the door would tend to cause any cold air which might enter to be carried into the flues 21 instead of into 75 chamber 11.

80 It will be obvious, therefore, that with the material being treated located within this open zone at the bottom of the chamber 11, such material will be subjected to the direct 85 action of the heated gases passing through the chamber above the material as well as of the radiant heat from the top of the chamber, and at the same time is subjected to the action of the heat of the wall which 90 supports this material and which is maintained heated by the passage of the gases through the flues 21, thus producing uniform results on the material. In addition, this particular arrangement enables the 95 chamber to be quickly heated to the desired 100 temperature, after which the temperature is maintained by reason of the ineffectiveness of any entering air to materially change this 105 condition.

110 Obviously, variations in temperature are readily obtainable by the use of a controllable burner. A preferred form of burner, where gas is the fuel employed, is illustrated in Fig. 7, in which 35 represents the gas inlet leading to an elbow 36 to which is connected a perforated pipe 37 having its free end closed, the elbow 36 and pipe 37 being preferably located within a tube 38, one end of which is connected to an air inlet 39, the opposite end being connected to a tubular arm 40 to which the nozzles 17 are connected. The tubular pipe 38 thus becomes a mixing chamber for the gas and air, the gas emerging from the perforations of pipe 115 37 at direct right angles to the direction of travel of the air entering through inlet 39, the result being that a maximum admixture 120 of air and gas is had within this tube, which 125 mixture is then led to the nozzles and into 130

the combustion chamber, the latter being supplied with its air for supporting combustion through air inlets 19. Through the various controls of the gas and the air inlet 39, 5 it will be readily understood that any desired admixture of air and gas may be provided, in addition to which, the air inlet opening 19 may be controlled through the use of suitable means such as removable 10 bricks, etc., for regulating the amount of air admitted to support combustion within the combustion chamber. Where high temperatures are desired, the air inlet 39 may be connected to a blast, and thus increase the effect, the addition of a blast being a well-known practice in this art.

It is to be understood, of course, that each chamber has its individual burner and control, so that while one chamber may be operating at one temperature, the other chamber may be operating at an entirely different temperature, each having its temperature maintained substantially uniform to perform the particular character of work intended.

It will be obvious that the same general principles may be employed in connection with a furnace having but a single chamber, or the structure may be amplified to increase 30 the number of chambers, it being necessary only to properly arrange the flues 21 and 22 to produce these results, this arrangement being along the lines indicated in Fig. 5.

While the present invention is more particularly adapted for use in the connection heretofore referred to, it is obvious that it may also be employed in connection with other uses, such for instance as the treatment 40 of cutlery, hardware, etc., the bridge wall having its height determined by the character of the work which the furnace is designed to perform.

While we have herein shown and described a preferred way in which the invention 45 may be carried into effect, it is obvious that changes and modifications therein may be required or desired to meet particular conditions incident to particular uses, and we desire to be understood as reserving the right to make any and all such changes and 50 modifications as may be found necessary in so far as the same may fall within the spirit and scope of the invention as expressed in the accompanying claims.

55 What we claim is:—

1. In a furnace of the character described, a chamber for the material to be treated, a combustion chamber in open communication with the treating chamber, means between 60 said chambers for producing a zone within the treating chamber substantially immune to direct flame contact of the furnace gases, said zone being adapted to receive the material being treated, an up-take 65 for the furnace gases, and an off-take be-

tween the treating chamber and the up-take, said off-take including parallel flues positioned below the plane of the hearth of the treating chamber, said flues being arranged in sets divided from each other, each set 70 having heating flues and a return flue, said heating flues having individual connection with the treating chamber, said return flue being connected to the up-take and the remaining flues of the set. 75

2. In a furnace of the character described, a chamber for the material to be treated, a combustion chamber in open communication with the treating chamber, means between 80 said chambers for producing a zone within the treating chamber substantially immune to direct flame contact of the furnace gases, said zone being adapted to receive the material being treated, an up-take for the furnace gases, and an off-take between the treating 85 chamber and the up-take, said off-take including parallel flues positioned below the plane of the hearth of the treating chamber, said flues being arranged in sets divided from each other, each set having a pair of 90 heating flues and a return flue, said heating flues having individual connection with the treating chamber, said return flue being connected to the up-take and the remaining flues of the set. 95

3. In a furnace of the character described, a chamber for the material to be treated, a combustion chamber in open communication with the treating chamber, a bridge wall between said chambers for producing 100 a zone within the treating chamber substantially immune to direct flame contact of the furnace gases, said zone being adapted to receive the material being treated, an up-take for the furnace gases, and an off-take between the treating chamber and the up-take, 105 said off-take including parallel flues positioned below the plane of the hearth of the treating chamber, said flues being arranged in sets divided from each other, each set having heating flues and a return flue, said heating flues having individual connection with the treating chamber, said return flue being connected to the up-take and the remaining flues of the set. 110

4. In a furnace of the character described, a chamber for the material to be treated, a combustion chamber in open communication with the treating chamber, a bridge wall between said chambers for producing a zone 120 within the treating chamber substantially immune to direct flame contact of the furnace gases, said zone being adapted to receive the material being treated, an up-take for the furnace gases, and an off-take between the treating chamber and the up-take, 125 said off-take including parallel flues positioned below the plane of the hearth of the treating chamber, said flues being arranged in sets divided from each other, each set hav- 130

ing a pair of heating flues and a return flue, said heating flues having individual connection with the treating chamber, said return flue being connected to the up-take and the 5 remaining flues of the set.

5. In a furnace of the character described, a treating chamber having an inlet at one end, a combustion chamber located at the opposite end of and in open communication 10 with the treating chamber, a bridge wall between said chambers to restrict the path of the furnace gases within the treating chamber, an up-take for the furnace gases, and an off-take between the treating chamber 15 and the up-take, said off-take including parallel flues positioned below the plane of the hearth of the treating chamber, said flues being arranged in sets divided from each other, each set having heating flues extending a distance substantially equal to the 20 length of the treating chamber, and a return flue, said heating flues having individual connections with the treating chamber, said return flue being connected to the up-take 25 and the remaining flues of the set.

6. In a furnace of the character described, a treating chamber having an inlet at one end, a combustion chamber located at the opposite end of and in open communication 30 with the treating chamber, a bridge wall between said chambers to restrict the path of the furnace gases within the treating chamber, said bridge wall having a projecting height less than half the distance between 35 the hearth and roof of the treating chamber, an up-take for the furnace gases, and an off-take between the treating chamber and the up-take, said off-take including parallel flues positioned below the plane of 40 the hearth of the treating chamber, said flues being arranged in sets divided from each other, each set having heating flues of equal length and a return flue, said heating flues having individual connection with the 45 treating chamber, said return flue being connected to the up-take and the remaining flues of the set.

7. In a furnace of the character described, a treating chamber having an inlet at one 50 end, a combustion chamber located at the opposite end of and in open communication with the treating chamber, a bridge wall between said chambers to restrict the path of the furnace gases within the treating 55 chamber, and an off-take for the furnace gases, said off-take being open through the bottom of the treating chamber adjacent the inlet to the latter, said off-take including a plurality of flues of equal length located below the floor and extending in the direction of length of the treating chamber, said flues having independent inlets and a common outlet.

8. In a furnace of the character described, 65 a pair of treating chambers each having a

combustion chamber individual to and in open communication with itself, a bridge wall between each treating chamber and its combustion chamber, and off-take means for the furnace gases, said means leading from 70 the treating chambers and including flues arranged in independent sets greater in number than the number of treating chambers, one of said sets being operative in connection with both chambers. 75

9. In a furnace of the character described, a pair of treating chambers each having a combustion chamber individual to and in open communication with itself, a bridge wall between each treating chamber and its 80 combustion chamber, and off-take means for the furnace gases, said means leading from the treating chambers, said means including a set of flues for and leading from each treating chamber and adapted to heat the 85 floor of such chamber and a third set leading from both chambers and aiding the remaining sets in the heating operation, each set opening to a pair of flues forming an off-take for the gases from the heating flues. 90

10. In a furnace of the character described, a pair of treating chambers each having a combustion chamber individual to and in open communication with itself, a bridge wall between each treating chamber 95 and its combustion chamber, and off-take means for the furnace gases, said means leading from the treating chambers, said means including a set of flues for and leading from each treating chamber and adapted to heat the floor of such chamber and a third set leading from both chambers and aiding the remaining sets in the heating operation, each set having an independent off-take flue. 100

11. In a furnace of the character described, a pair of treating chambers each having a combustion chamber individual to and in open communication with itself, a bridge wall between each treating chamber and its combustion chamber, and off-take 105 means for the furnace gases, said means leading from the treating chambers, said means including a set of flues for and leading from each treating chamber and adapted to heat the floor of such chamber and a third set 110 leading from both chambers and aiding the remaining sets in the heating operation, each set having an independent off-take flue, and also having communication to an off-take flue common to both sets. 115

12. In a furnace of the character described a pair of treating chambers each having a combustion chamber individual to and in open communication with itself, a bridge wall between each treating chamber and its combustion chamber, and off-take means for the furnace gases, said means comprising a plurality of flues located below the plane of the hearth of the treating chambers, said flues being arranged in sets 125 130

divided from each other, each set having heating flues and a return flue, a heating flue of one set being operative with respect to the treating chamber heated by the heating flues of another set.

13. In a furnace of the character described, a pair of treating chambers each having a combustion chamber individual to and in open communication with itself, a bridge wall between each treating chamber and its combustion chamber, said bridge wall having a projecting height less than half the distance between the hearth and roof of the treating chamber, and off-take means for the furnace gases, said means comprising a plurality of flues located below the plane of the hearth of the treating chambers, said flues being arranged in sets divided from each other, each set having heating flues and a return flue, the flues on opposite sides of the division between sets operating in connection with the same treating chamber.
- 15 means for the furnace gases, said means comprising a plurality of flues located below the plane of the hearth of the treating chambers, said flues being arranged in sets divided from each other, each set having
- 20 heating flues and a return flue, a heating flue of one set being operative with respect to the treating chamber heated by the heating flues of another set.

14. In a furnace of the character de-

scribed, a pair of treating chambers each having a combustion chamber individual to and in open communication with itself, a bridge wall between each treating chamber and its combustion chamber, and off-take means for the furnace gases, said means comprising a plurality of flues located below the plane of the hearth of the treating chambers, said flues being arranged in sets divided from each other, each set having heating flues and a return flue, the flues on opposite sides of the division between sets operating in connection with the same treating chamber.

In testimony whereof, we affix our signatures in presence of two witnesses.
